UNITED STATES PATENT OFFICE.

LOUIS J. VAN GELPEN, OF CINCINNATI, OHIO.

INKING-MACHINE.

1,249,563.

Specification of Letters Patent. Patented Dec. 11, 1917.

Application filed February 5, 1917. Serial No. 146,763.

To all whom it may concern:

Be it known that I, LOUIS J. VAN GELPEN, a citizen of the United States, residing at the city of Cincinnati, in the county of Hamilton and State of Ohio, have invented 5 certain new and useful Improvements in Inking Machines, of which the following is a specification.

My invention relates to that class of ink- 10 ing machines designed to ink or color the edges of leather or other material, and the object of my invention is to produce a machine of this character which will be simple in construction, cheap of manufacture and 15 highly efficient in use.

A further object of my invention is to produce a machine of this character which will distribute the ink or color evenly and uniformly on the edges of the material so 20 that said edges will all be the same in appearance color and density in their surface edge appearance.

Another object is to provide a machine 25 which will use the ink or coloring matter as it comes from the ink holding pot in a pre-determined quantity so that uniformity of ink distribution will result on the edges of the material.

Another object is to use a revolving brush 30 which receives the ink from a felt pad over the surface of which it passes as it revolves, so that the ink will always be the same in density and quality and be fresh and not become gummy or viscous but always retain 35 its proper liquid standard.

Another object consists in using an ink distributing or receiving vessel which can be opened and closed and which can be adjusted to take up the wear of the brush and 40 felt.

Another object consists in a peculiarly shaped feed plate to enable the operator to feed the material evenly and uniformly to the brush.

45 The various features, objects and advantages of my invention will readily become apparent from the following specification.

In the accompanying drawing forming part of this specification;

Figure 1, is a plan view partly in section 50 to illustrate construction,

Fig. 2, is a side elevation partly broken away and in section to illustrate construction,

Fig. 3, is a section taken on line 3—3 of 55 Fig. 1, and

Fig. 4, is a side view of part of the inking vessel, brush and connecting parts.

On a base 1, I mount the ink holding pot or vessel 2, of a cylindrical shape and having 60 a top or lid 3 which is removable.

On the front end of base 1, I place an outwardly extending arm 4, this arm is also a bearing for the drive shaft 5. This shaft extends through the base 1, and is supported 65 in the rear by bearing 6 and carries at this end the pulley 7. At the extreme forward part of arm 4 I form a pocket or recess 8 covered by a plate 9. The shaft 5 ends in this pocket 8 and carries at this point a 70 spiral gear wheel 10. A short shaft or spindle 12 extends up into this pocket 8 and carries at this point a spiral gear wheel 13, which meshes with spiral gear 10 on shaft 5. The spindle 12 extends out from shaft 5 at 75 right angles and is attached to the inking brush 14, so that when the shaft 5 is revolved its gear 10 will mesh with gear 13 and drive the spindle 12 and consequently the brush 14 will be revolved.

80 This brush is circular in contour and may be made out of any suitable material which is yielding and resilient. The ink receiving vessel which receives the ink from the ink holding pot 1, is preferably formed of two halves or shells 15 and 16 hinged together at the rear end, at point 17 to a bracket 18 which is attached to the arm 4 and is also adjustable to the wear of the brush and felt. To do this I place a slot 19 in bracket 18 so 85 that the parts 15, 16 and 17 and the bracket 18 can be slid backward and forward and tightened up by screw 20 which screws into the arm 4 and passes through said slot 19.

The bottom or under shell of the ink receiving vessel 15 is the part which receives the ink directly as it drops from the pipe 21 into groove 22 from which it runs into the vessel part 15. This lower part 15 also carries the feed plate 23 and is usually made integral therewith.

- On this part 15 I place a stop lug 24 and when it is raised to normal position the handle lever 25, which is pivoted on arm 4, on the depending lug 26, is moved laterally until it strikes and passes under lug 24 and against stop finger 27—thus holding part 15 up in position. By reversing handle 25 the part 15 can be swung down so that it can be cleaned or repaired readily. The upper part or shell 16 is a guard and fits into the lower part 15, the lug 28 limiting its downward movement.
- 20 This guard or shell part 16 can be swung up to be cleaned or repaired. In Fig. 4 I show the parts 15 and 16 extended and out of normal position.

- 25 At the point shown in the shell 15 at its inside, I place a piece or section of felt or any equivalent material 30, holding the same in position by a strip of metal 31 formed and shaped to hold it thereon. I provide adjustment screw 32—32, so that the felt can be moved upward or downward to accommodate wear of brush 14 and felt 30.

- 30 The guard or shell 16 has a cut away part 33 which fits down adjacent to feed plate 23 so that a space will be left through which to pass the material to be inked, as it is fed past the brush.

In pipe 21 I place a regulating valve 34 to increase or diminish the flow of ink from the ink holding pot 2.

- 40 The feed plate 23 is curved, that is highest at the middle and rounding off toward the sides as shown by character 35 (this designates the highest point of plate 23.) By making the surface of this plate rounded it is more convenient for the operator to pass the material over the face of said feed plate to the brush and the brush always operates against said material at the highest and the same point, so that the distribution of ink will always be the same and the brush will not under any circumstances force or place any ink on the upper, glazed or finished surface of the leather or other material to be operated upon.

- 50 55 The brush being circular and preferably narrow, and the bristles or material comprising it being long so that it will yield or bend and not act in a stiff or rigid manner, the ink will always be properly placed on the material evenly if the operator happens to not feed the material uniformly or feeds it in too far.

It is obvious that the specific construc-

tion herein described can be modified and changed without departing from the principle and spirit of the invention and I wish to be understood as claiming that such modifications will fall within the scope of my invention.

What I claim as new and my invention and desire to secure by Letters Patent is:

1. In an inking machine of the character described, an ink feeding source of supply, an ink receiving vessel, a revolving brush therein, means for revolving the same, a 75 pad in said receiving vessel, for taking up the ink, the revolving brush taking the ink off of said pad.

2. In an inking machine of the character described, an ink receiving vessel, a pad on 80 the inner side thereof, a revolving brush, means for feeding ink to said pad, the revolving brush passing over the pad as it revolves, to carry the ink to the material to be inked.

3. In an inking machine of the character described, an ink receiving vessel, formed of two movable parts, capable of being opened and closed, a revolving brush therein, an inked pad in said vessel, the brush in revolving taking the ink off of said pad.

4. In an inking machine of the character described, an ink receiving vessel and means for feeding a predetermined amount of ink thereto, a brush inclosed in said vessel for 95 gathering said ink as it is fed, to distribute the same upon the material to be inked.

5. In an inking machine of the character described, an ink receiving vessel and means for feeding a predetermined amount of ink thereto, a brush inclosed in said vessel for gathering said ink as it is fed, to distribute the same upon the material to be inked and means for enabling the material to be held against said brush.

100 105 6. In an inking machine of the character described, an ink receiving vessel and means for feeding a predetermined amount of ink thereto, a brush inclosed in said vessel for gathering said ink as it is fed to distribute the same upon the material to be inked and a rounded stationary feed plate upon which the material is fed to the brush.

7. In an inking machine of the character described, an ink receiving vessel having a section of felt secured therein, and means for feeding a predetermined amount of ink to said felt, a brush in said vessel for gathering the ink off of said felt to distribute the same upon the material to be inked.

110 115 8. In an inking machine of the character described, an ink receiving vessel having a section of felt secured therein, and means for feeding a predetermined amount of ink to said felt, a brush in said vessel for gathering the ink off of said felt to distribute the

same upon the material to be inked, said ink receiving vessel formed of two hinged parts capable of being opened and closed.

9. In an inking machine of the character described, an ink receiving vessel having a section of felt secured therein, and means for feeding a predetermined amount of ink to said felt, a brush in said vessel for gathering the ink off of said felt to distribute the 10 same upon the material to be inked, said

ink receiving vessel formed of two hinged parts capable of being opened and closed, the said ink receiving vessel also capable of being moved forward and backward.

Witness my hand at Cincinnati, Ohio, January 31st, 1917.

LOUIS J. VAN GUELLEN.
